CLOTH DRYING PROCESS AND APPARATUS

Harry D. Learnard, Andover, Mass., assignor to
Pacific Mills, Lawrence, Mass., a corporation of
Massachusetts

Application June 15, 1940, Serial No. 340,752

3 Claims.

(Cl. 34—41)

This invention relates to a novel process for drying cloth in long lengths and a novel machine for the purpose.

One of the objects of the present invention resides in an improved process for drying cloth which results in quicker, more economical and more uniform drying, with little or no tendency for the cloth to change its dimensions either warp-wise or weft-wise during drying.

A further object of the invention is a novel cloth drying process which dries the cloth smooth and flat and improves the hand and feel of the cloth.

Heretofore, cloth has been dried by passing the cloth about a plurality of cylindrical drying drums or cans internally heated by steam or other suitable medium, the drums each being driven by a suitable power source and each exerting a driving effect on the cloth. In such a drier the cloth is often slack about many drums with consequent loss in drying effect and uneven drying.

In accordance with the present invention the cloth to be dried itself constitutes the driving element of many of the drums while others of the drums or other cloth driving means is utilized to drive the cloth. With this arrangement the cloth is pulled tight upon the drums it drives and hence the cloth is in intimate contact with the drums and dries rapidly and uniformly. All drums of the same type turn at the same peripheral speed and hence the warp and weft strands during the passage around the drums are in the same relative condition at each drum and are set in that relative condition while wet so that the cloth is not distorted. Due to the tightness of the cloth on the drums, the cloth is made smooth and free from wrinkles and is of more uniform width and acquires great smoothness and a fine hand and feel.

Hence a further object of the invention is a method of drying cloth wherein the advancing cloth constitutes the driving element of some of the drying drums about which it passes.

Another object is the provision of a cloth drier wherein the cloth passed through the drier constitutes the driving element for at least some of the drying drums about which it passes.

A further object is generally to improve upon processes and machines for drying cloth.

Fig. 1 is a side elevation of one form of drier constructed in accordance with the present invention.

Fig. 2 is a sectional detail through a bearing for a drying drum, taken along line 2—2 of Fig. 1.

Various arrangements of driers can be made to

operate in accordance with the present invention. The type of drier to be employed will be selected according to the nature of the cloth and the facilities of the plant.

Fig. 1 illustrates a drier which has proven satisfactory in performing the present invention. The drier comprises a lower horizontal row of smooth faced hollow metal cylindrical drying drums or cans 10 of equal diameter journaled in hollow brackets 12 supported on a hollow lower frame 14 and each provided with a similar driving sprocket 16. The drier also includes a horizontal upper row of similar drying drums 18 which are located between but out of contact with the drums of the lower roll and having shafts 20, Fig. 2, which are mounted in anti-friction as ball bearings 22 carried by hollow brackets 24 supported by a hollow upper frame 26. The upper drums are not provided with driving means and are intended to be driven and rotated entirely by the cloth in contact with said upper drums.

The lower rolls are driven at the same peripheral speed by a chain 28 which is in engagement with all of the sprockets of the lower rolls and is passed about a driving sprocket 30 driven by any suitable power source. The cloth A passes through a tensioning device 32 and thence alternately over the lower and upper drums and from one end to the other of the drier and thence passes to a roll-winding device 34 where the dry cloth is wound into a roll 36.

A drying medium, as steam, is admitted to the drums in any suitable manner. As illustrated in Fig. 2, the drum supporting bracket is hollow and has an internal passage 38 that opens to the internal passage 40 of the supporting frame, which passage receives steam or other drying medium at suitable pressure and temperature from any suitable source. The drum shaft has an axial passage 42 therethrough opening into the bracket passage at one end and into the drum at the other end through which the steam can flow into and circulate about the interior of the drum. A condensate pipe 44 also passes loosely through the shaft passage and through and is supported by the bracket and connects with a pipe 46 of a manifold 48, Fig. 1, by which excess condensate can be forced from the drum by the steam pressure.

As thus arranged, the cloth is driven by each of the lower drums 10 and drives each of the upper drums 18. The cloth thus is pulled tightly onto the upper drums and lies flat and smooth thereon so that the drying is rapid and uniform

and the dry cloth is smooth and has a superior feel. The lay of the warp and weft strands is not disturbed and the cloth dries free from distortion and with uniform width. There can be more than one freely rotatable drum between a pair of power driven drums.

However arranged in accordance with this invention, the cloth constitutes the driving element for some of the drying drums and thereby is caused to be pressed tightly and smoothly in contact with such drums and also with the drums which drive the cloth so that rapid uniform drying of the cloth under uniform width free from material change of dimensions is obtained. The drying drums have the usual smooth metal cylindrical faces against which the cloth bears and the cloth driving drums advance the cloth at uniform speed through the drier.

Since the drier consists of a series of drum-couples comprising an idler drum and a driving drum, the cloth web is caused to be wrapped snugly against the surfaces of both drums by the pull of a driving drum, but since the driving drums of all couples turn at the same peripheral speed there is no tendency for the successive couples to elongate the web warpwise. There is inherent slip between the web and the driving and idler drums, particularly as the steam-heated drums vaporize the moisture in the cloth at the surfaces of the drums. The effect of the pressure and the slip is to iron the cloth and improve its finish. The slip or relative movement between the web and the drums is in opposite directions on the two drums of a drum-couple so that any tendency of a driven drum to elongate the web by rubbing out the weave crinkles is offset by the tendency of the cooperating idler drum to shorten the web by rubbing the web in the opposite direction to restore the weave crinkles. Thus the herein described apparatus not only dries the cloth but gives it an improved ironed finish without material web elongation.

I claim:

1. The method of drying cloth and improving the condition of the surfaces thereof without substantial change in warpwise dimensions thereof in a drier having power-driven and idler drying drums having smooth cloth-engaging peripheries, which method consists in passing the cloth alternately about a power-driven and an idler drum in succession, driving the power-driven drums at equal peripheral speeds by application of power external of the drier and advancing the cloth by

the friction between the cloth and the power-driven drums, driving the idler drums solely by the friction between the advancing cloth and the idler drums, internally heating the drying drums above the boiling point of the moisture in the cloth and above the temperature of the surrounding atmosphere to form steam between the cloth and the drums providing for slippage of the cloth on the drums which causes ironing of the cloth surface.

2. A cloth ironer and drier having in combination a series of drying and ironing drums having smooth peripheral surfaces, a second series of drying and ironing drums, each separate drum of one series adapted to receive the cloth from a separate drum of the other series, means to conduct heating steam to the interiors of said drums, delivery means adapted to deliver cloth under tension to the first drum of one of said series of drums, mechanical means for driving the drums of said first series at the same peripheral speed and at a speed greater than the speed of the cloth on said drums thereby ironing the cloth in one direction by advancing said drum surfaces faster than the cloth is delivered to said drums, drums of the second series being devoid of mechanical driving means whereby said drums are adapted to be driven solely by the cloth in contact therewith and at a peripheral speed slower than the speed of the cloth thereon thereby ironing the cloth in the opposite direction, and means adapted to receive the dry, ironed cloth from said series of drums.

3. The method of drying cloth, without material change in the warpwise dimension of said cloth, which comprises delivering the cloth under tension to the surface of a heated drying drum, heating the cloth by the heat of the drum, drying and ironing said cloth on said drum by rotating said drum mechanically to advance the surface of said drum faster than said cloth, delivering the cloth from said drum to another drying drum, heating the cloth by the heat of the drum, and ironing said cloth on said latter drum, as said drum is rotated solely by said cloth, by advancing the cloth faster than the surface of said drum, and tightening the cloth on the surface of said last named drying drum by delivering the cloth to a third drying drum and ironing the cloth on said third drum by rotating said third drum mechanically at equal peripheral speed with the first drum, to advance the surface of said drum faster than the cloth.
